TWO FACED GOLF CLUB HEAD

Rodger D. Brouwer, Bristol, Conn.

Application November 13, 1956, Serial No. 43,729

Term of patent 14 years

(Cl. D34—5)

Fig. 1 is an elevational view of the club head showing my new design.

Fig. 2 is a full scale view of one of the hitting faces of said golf club head.

Fig. 3 is a full scale view of the other hitting face of said golf club head.

Fig. 4 is an end view of said golf club head shown on a reduced scale.

I claim:

The ornamental design for a two faced golf club head, substantially as shown.
